UNITED STATES PATENT OFFICE.

THOMAS R. KENNEDY AND EDWARD J. KING, OF ROCHESTER, NEW YORK, ASSIGNORS TO THE CO-OPERATIVE FOUNDRY COMPANY, OF SAME PLACE.

DESIGN FOR A STOVE OR RANGE.

SPECIFICATION forming part of Design No. 31,606, dated October 3, 1899.

Application filed September 12, 1899. Serial No. 730,272. Term of patent 7 years.

To all whom it may concern:

Be it known that we, THOMAS R. KENNEDY and EDWARD J. KING, citizens of the United States, residing at Rochester, in the county of Monroe and State of New York, have invented and produced a new and original Design for Stoves or Ranges; and we do hereby declare the following to be a full, clear, and exact description of the same, taken in connection with the accompanying drawing.

The leading feature of our design consists in the shape and configuration of the stove or range as a whole and of the ornamentation applied to its various parts.

15 The stove or range is composed of the substantially rectangular body A, supported upon a base B, consisting of the lower flange or plain border *b* and the oblong beaded and ribbed portion *b'*, above which is provided 20 the molding *b*². Extending from one end of the stove is the reservoir-section C, having the ornamental bracket C' at the lower edge and having the panel D in relief and ornamented as shown.

25 E indicates the oven-door, having the border F, provided with the scroll ornamentation *f*. Arranged within the border F is the central panel G, having the rounding corners and edges covered with the scroll and leaf ornamentation H, and arranged upon the center of the panel is the plate *g*, having the aperture at its center surrounded by the circular molding *g'*.

I indicates ornamented brackets arranged at the lower corners of the oven-door, and K 35 and L the decorative latch member, located upon the upper side thereof.

M indicates a small door provided beneath the oven-door, surrounded upon the ends and lower side by the ornamented panel N.

40 O indicates the fire-pot door, arranged upon the upper corner of the body, provided with the scroll ornamentation shown, and having brackets *o* on the body extending at the sides of the door.

45 P indicates the grate-door, provided beneath the door O and ornamented upon the diagonal corners by the scroll and leaf ornamentation *p*.

Q indicates the ash-pit door, having the plain center *q* and the conventional leaf ornamentation R across the top and bottom.

50 Arranged upon the end of the stove is the grate-door S, having the damper T.

U indicates a plain band or border provided 55 upon the corners and other portions of the body.

W indicates the band at the stove-top.

We claim—

The design for a stove or range substantially as herein shown and described.

THOMAS R. KENNEDY.
EDWARD J. KING.
